UNITED STATES PATENT OFFICE.

MARY D. BENSON, OF NEW YORK, N. Y.

DESIGN FOR A COMBINED BIB AND APRON OR SIMILAR ARTICLE.

Application filed August 23, 1922. Serial No. 3,533. Term of patent 14 years.

To all whom it may concern:

Be it known that I, MARY D. BENSON, a citizen of the United States, residing in the borough of Manhattan, in the city, county, and State of New York, have invented a new, original, and ornamental Design for Combined Bib and Apron or Similar Article, of which the following is a specification, reference being had to the accompanying drawing, forming a part thereof.

Figure 1 is a front plan view of a combined bib and apron or similar article showing my new design, while Figure 2 is a rear plan view thereof.

I claim:

The ornamental design for a combined bib and apron or similar article as shown.

MARY D. BENSON.
